UNITED STATES PATENT OFFICE

HERBERT A. ACER, OF MEDINA, NEW YORK, ASSIGNOR TO ACER & WHEDON, INC., OF MEDINA, NEW YORK, A CORPORATION OF NEW YORK

FURNACE TOP

Application filed May 27, 1930. Serial No. 456,105.

The invention comprehends a furnace top which may be shipped in knockdown form and which may be quickly set up where the furnace is to be erected.

5 The invention further comprehends a furnace top having a sand rail which may be quickly adjusted in position and which will hold a considerable quantity of sand without danger of the sand falling on the floor. 10 The use of this sand made possible by the sand rail increases the heat efficiency of the furnace.

15 The invention further comprehends a sand rail for furnace tops which may be shipped in knockdown form, the construction being such that the sand rail may be quickly set up in place.

20 The invention furthermore comprehends a furnace top having lateral outlets and a top member, the sides of which diverge upwardly from a central point to positions above the lateral outlets.

25 The invention furthermore comprehends a top member for furnaces which diverges upwardly and which has a sand rail, the top member and sand rail serving to support sand on the furnace to increase the heat efficiency of the furnace, the top member and the sand rail having a construction which 30 makes it possible to erect the furnace top quickly when the parts are shipped in knockdown form.

35 The invention furthermore comprehends a top member for furnaces made in one piece and with a cut-away portion, the sides of the top member at the cut-away portion diverging outwardly and there being interlocking members on the top member adjacent its cut-away portion, the top member normally assuming an inverted conical shape with its periphery disposed in a groove in a rail member.

40 Additional objects of the invention will appear in the following specification in which the preferred form of the invention is described.

In the drawings similar reference characters refer to similar parts in all the views, of which

50 Figure 1 is a side elevation of the top mem-

ber of the furnace embodying my invention, Figure 2 is a plan view of Figure 1,

Figure 3 is an enlarged sectional view on the line 3—3, of Figure 2,

Figure 4 is an enlarged sectional view on the line 4—4, of Figure 2,

Figure 5 is a fragmentary view showing one of the locking members,

Figure 6 is a view illustrating a section of the top of the furnace,

Figure 7 is a plan view of the top member of the furnace before it has been bent into conical shape,

Figure 8 is a fragmentary view illustrating the fastening member at one side of the cut-away portion, and

Figure 9 is a perspective view of the rail member having a groove for the periphery of the top member and the sand rail above the said groove.

By referring to the drawings it will be seen that the top of the furnace is constructed of a plurality of sections 10, which are best illustrated in Figure 6 of the drawings, each of these sections 10 having cuts 11 with stamped-up portions 12 adjacent the cuts, the said stamped-up portions serving as one set of the locking members for the sections 10. The other edges of the sections 10 are bent back at 13, forming members 14 which are disposed close to the body of the sections 10, the members 14 extending outwardly at 15 and at 16 substantially parallel with the body of the sections 10 to the positions 17, where they are bent inwardly and again parallel with the body of the sections 10 to form engaging edges 18.

It will be understood by referring to Figure 4 of the drawings, that the stamped-up portions 12 forming the locking members pass between the engaging edges 18 and the members 14 on an adjacent section 10, so that the stamped-up portions 12 forming locking members will engage the edges 18 to obtain a firm locking means to hold the sections 10 in position, these sections 10 preferably having their lower edges bent at 19 so that the lower portions of the sections 10 may fit in the body 20 of the furnace.

Before these sections 10 are secured to-

gether the rail member 21 is preferably disposed in position, this rail member 21 being preferably in one piece with a groove 22 and a sand rail 23 extending above the groove. 5 A top member 24 is provided, this top member 24 having a cut-away portion 25, the sides of which diverge outwardly from the central portion 26, there being a stamped-up portion 27 on the top member 24 at one side of this 10 cut-away portion 25 and there being a locking member 28 at the other side of the cut-away portion 25.

This locking member 28, as best illustrated in Figure 8 of the drawings, is secured to the 15 top member 24 at the side 29 of the cut-away portion by bending the locking member 28 around the said side 29 of the cut-away portion and making oblique indentures 30 which press inwardly the locking member 28, to- 20 gether with the top member 24 at its cut-away portion, the locking member 28 having a bent portion 31 with a bent edge 32 for en-gaging the locking member formed by the stamped-up portion 27. It will be under- 25 stood that when this top member 24 is bent in conical shape the locking member formed by the stamped-up portion 27 may be pressed into locking engagement with the edge 32 of the locking member 28 to secure the top mem- 30 ber 24 in conical shape, this top member 24 in conical form being inverted and having its periphery 33 disposed in the groove 22 in the rail member 21 when the ends 34 of the rail member 21 are secured together by means 35 of bolts 35 which are disposed through ori-fices in lugs 36 which are secured to the ends 34 of the rail member. With this construc-tion the top member 24 is securely held in place relatively to the rail member 21 and the 40 rail member is secured in permanent form for use in the erection of the top of the furnace.

The rail member 21 with its top member 24 having been set up in the manner set forth, 45 the bottom 37 of the rail member 21 is disposed within the top 38 of the sections 10 which are then secured together in the manner described, the open ends of the sections 10 being then secured together by means of 50 bolts 41, which are disposed in openings in lugs 40 which are secured to the ends of the sections 10.

In this manner the rail member is set up from the knockdown parts and is secured in 55 position at the top of the sections 10, these sections 10 being secured together in the manner set forth, the bottoms of the sections 10 being normally disposed within the walls of the body 20 of the furnace.

60 As illustrated in Figure 3 of the drawings, the sides of the top member 24 diverge upwardly from a central point to the periphery 33 of the top member which is disposed in the groove 22 of the rail member 21.

65 What is claimed is:

1. In a furnace top, a horizontally dis- 70 posed circular rail member having a central opening and a groove extending radially from the central opening, the rail member having a sand rail extending above the groove, and a top member having a circular periphery disposed to close the central open-ing and having its periphery normally dis- 75 posed in the groove.

2. A furnace having a body portion with a sand rail around a central opening, there be- 75 ing a bead below the sand rail, the bead ex-tending radially from the central opening and a top member disposed to close the cen-tral opening with its periphery disposed in the bead.

3. A furnace having a body portion with a sand rail around a central opening, there be- 80 ing a bead below the sand rail which extends radially from the central opening, and an inverted conical top member disposed to close the central opening with its periphery ex-tending into the bead.

4. A furnace having a body portion com- 90 prising an outwardly extending bead and having a portion projected upwardly above the bead to form a sand rail, and a member for closing the top of the body disposed with its periphery in the bead.

5. A furnace having a body portion com- 95 prising an outwardly extending bead and project-ing upwardly above the bead to form a sand rail, and a member for closing the top of the body, the member diverging upward- 100 ly from a central point with its periphery disposed in the bead.

6. In a furnace top, a horizontally disposed rail member having transverse ends, the rail member extending outwardly and inwardly from end to end to form a bead, means to se- 105 cure the ends of the rail member adjacent each other, and a top member disposed within the rail member with its periphery dis- 110 posed in the bead.
